UNITED STATES PATENT OFFICE

2,436,166

TAPE CUTTING ATTACHMENT FOR SPOOLS

Stephen Gaydos, Jr., Gary, Ind.

Application February 28, 1945, Serial No. 580,245

2 Claims. (Cl. 242—55.5)

1

The present invention relates to new and useful improvements in spools for adhesive tape and similar material, and the invention has for its primary object to provide a cutter carried by the spools for cutting the tape.

An important object of the present invention is to provide a cutter of this character adapted for movement around the inside of the flanges of the spool so that the cutter may be positioned at a desired point in the spool for cutting the tape at a desired length.

A further object of the invention is to provide means for pivotally mounting the cutter in the spool, together with finger-gripping means for firmly holding the cutter against the tape while the latter is being cut.

A still further important object of the invention is to provide means to prevent the movement of the cutter outwardly beyond the flanges of the spool to expose the cutting edge thereof, and thus avoid injury to persons handling the spool.

A still further object is to provide a device of this character of simple and practical construction, which is efficient and reliable in operation, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like reference numerals refer to like parts throughout, and in which:

Figure 1 is a side elevational view of the spool,

Figure 2 is a sectional view taken substantially on a line 2—2 of Figure 1,

Figure 3 is a transverse sectional view taken substantially on a line 3—3 of Figure 2,

Figure 4 is an enlarged transverse sectional view of the spool showing the cutter mounted for rotation therein, and

Figure 5 is an enlarged perspective view of the cutter with parts of the spool shown in section.

Referring now to the drawing in detail wherein, for the purpose of illustration, I have disclosed a preferred embodiment of the invention, the numeral 5 designates a spool generally of a type adapted for containing adhesive tape or similar material 6 rolled on a hub 7 supported between the flanges 8 of the spool.

The opposed surfaces of the flanges 8 are formed with annular grooves 9 within which runners 10 are slidably mounted for movement circumferentially at the inside of the spool in the

2

grooves 9, the runners being connected by a pin 11 extending transversely of the spool, and on which a blade 12 is pivotally mounted by means of bearings 13 formed at the rear edge of the blade.

5 The front edge of the blade is beveled, as indicated at 14, to provide a sharp cutting edge adapted to bear against the periphery of the rolled tape in a manner as indicated in Figure 3 of the drawing.

10 Also pivoted on the pin 11 is a finger-gripping tongue 15 projecting rearwardly from the pivoted end of the blade 12 and providing finger-gripping means for pivotally actuating the blade to swing the cutting edge thereof into and out of engagement with the tape, and to exert a desired pressure on the cutting edge of the blade to hold the same firmly against the tape while sections of the tape are cut at the sharpened edge 14 thereof.

15 The runners 10 are provided with inwardly projecting stops 16 overlying the blade 12 to limit outward swinging movement thereof beyond the peripheral edges of the flanges 8 and thus prevent projecting of the sharpened edge of the blade outwardly beyond the edges of the spool to avoid injury to persons while handling the spool.

20 The tongue 15 is formed at its inner end with a stop lug 17 adapted to bear against one side of the blade 12, as shown in Figure 3, when the tongue is raised to force the blade downwardly against the tape and thus firmly hold the tape while the latter is being cut. The tongue 15 may normally swing downwardly into a position between the flanges of the spool, as shown in Figure 4, when not in use. A stop lug 18 is also formed on the bottom of the tongue 15 to bear against the other side of the blade 12 and limit downward movement of the tongue. By depressing the tongue 15 with the stop lug 18 bearing 25 against said other side of the blade 12, said blade may be swung to disengage the same from the tape 6, when desired.

30 In view of the foregoing description taken in conjunction with the accompanying drawings, it is believed that a clear understanding of the construction, operation and advantages of the device will be quite apparent to those skilled in this art. A more detailed description is accordingly deemed unnecessary.

35 It is to be understood, however, that even though I have herein shown and described a preferred embodiment of my invention that the same is susceptible to certain changes fully comprehended by the spirit of the invention as herein 40 described and the scope of the appended claims.

Having thus described the invention, what I claim is:

1. A tape cutter for tape spools and comprising a blade positioned between the flanges of the spool, said flanges having annular grooves in their opposed faces, runners adapted to travel in the grooves, a hinge pin connected to the runners, a blade pivoted at one edge on said pin, and a finger grip pivoted on the pin and having means thereon for engaging opposite sides of the blade to raise and lower the other edge thereof upon pivotal movement of said grip.

2. A tape cutter for tape spools and comprising a blade positioned between the flanges of the spool, said flanges having annular grooves in their opposed faces, runners adapted to travel in the grooves, a hinge pin connected to the runners, a blade pivoted at one edge on said pin, means for manually raising and lowering the

other edge of the blade, and a stop carried by one of the runners engageable by the blade to limit its raising movement.
